UNITED STATES PATENT OFFICE.

CHARLES KNEVYL SUGDEN, OF LONDON, ENGLAND.

SOUND-REPRODUCING APPARATUS.

Application filed January 23, 1924, Serial No. 687,999, and in Great Britain February 14, 1923.

This invention relates to sound-reproducing apparatus and has for its object to provide an apparatus adapted to operate either as a phonographic sound reproducing machine or as a receiver of wireless signals.

According to the invention the sound reproducing machine is so provided that a wireless receiver amplifying device may be substituted for the sound box or for the sound box and the member carrying it in order that the horn or sound amplifier of the machine may serve as a wireless loud speaker.

According to the invention, moreover, in the application to sound reproducing machines provided with an internal horn or sound amplifier and a cover or lid, a wireless receiving set may be installed within the interior of the cover or lid, which may for the purpose be provided of corresponding depth. Similarly, a wireless receiving set may alternatively be fitted or contained within the cabinet of a pedestal or like sound-reproducing machine.

The wireless receiver amplifying device may be of any desired construction and may be adapted to be fitted upon the sound reproducing machine in any appropriate manner. Thus, gramophones provided with a pivoted tone arm for carrying the sound box may be adapted for the removal of the tone arm and for the fitting in place of the wireless amplifying device. The tone arm may for this purpose be detachably mounted by means of a socket with a bayonet joint attachment and the wireless amplifying device be similarly provided with a bayonet joint device. Again, the tone arm and wireless amplifying device may each be provided with a flange or lugs adapted to be engaged by a screw down annular holding device fitted upon the machine, or each may be provided with a plain sleeve adapted slidably to fit within a socket forming the inner end of the horn or sound amplifying device of the machine. Again, the wireless amplifying device may be adapted merely to replace the sound box and be fitted with corresponding means for connection to the tone arm or other sound box carrying member.

The invention is also not limited to any particular manner of fitting a wireless receiving set to a gramophone or other sound reproducing machine. Thus, it may be fitted as an integral part of the instrument or

it may be provided as a self-contained unit adapted to be fitted into the lid or body of the machine and to be secured in position by retaining devices.

Several constructions of sound-reproducing apparatus provided according to the invention are illustrated, by way of example, in the accompanying diagrammatic drawings in which Figures 1, 2 and 3 are respectively perspective views of different constructions.

In carrying the invention into effect as applied to gramophones of the pedestal type and according to the construction represented in Figure 1 of the drawings, the lid or cover *a* is provided of greater depth than is usual and a wireless receiving set, comprising the elements necessary according to the desired range of reception, is assembled upon a panel *b* which is mounted within the lid or cover *a* and is secured in position by such means as screws, fastening devices or clips in order that it may readily be removed when necessary. A wireless sound amplifying device *c* comprising a cylindrical or other form of casing is fitted with a socket connector, similar to that provided upon the sound box *d*, in order that it may be mounted upon the tone arm *e* in substitution for the sound box. Terminals *c*¹ are provided for connection to flexible leads *c*² which are carried through the panels *b*. When the wireless receiving set is not required for use the sound amplifying device *c* is conveniently received into a recess or hole formed in the top plate *f* of the cabinet and serving alternatively to receive the sound box *d* when this is not in use. The panel *b* is advantageously provided with a hinged section *b*¹ serving to close a compartment at the rear of the panel in which thermionic valves may be disposed. Provision may be made in the lid also for the reception of the electric batteries required for the operation of the wireless receiving set but these are conveniently housed in the lower part of the cabinet.

In the construction represented in Figure 2, the panel *b* carrying the elements comprising the wireless receiving set is disposed in the lower part of the cabinet behind the doors *h* which usually cover a compartment adapted to hold records. The panel is conveniently carried within a drawer *i* or formed to slide into and out of the cabinet as a drawer in order that the

various elements may be rendered accessible. The panel may, however, be secured in position by screws, clips or other fastening devices. The sound amplifying device *c* as before is adapted to be substituted in position for the sound box *d*. The batteries are conveniently enclosed within the cabinet to the rear of the panel *b* and in the drawer *i*, or they may be rendered accessible by a door provided in the rear of the cabinet.

Similarly, in the case of sound reproducing apparatus having a cabinet of horizontal rectangular form, divided by a transverse partition into two compartments, the sound reproducing apparatus is disposed in the one compartment and the panel carrying the wireless receiving set in the other compartment, the lower portion of which may serve to receive records. The panel may conveniently be covered when the wireless set is not in use, by a sliding or revolving shutter.

According to the modified construction represented in Figure 3, the panel *b* is mounted in a casing *j* serving to receive the elements of the wireless receiving set fitted upon a board *k* which serves to close the cover or lid *a* or to form a bottom thereto and is hinged both to the cover or lid *a* and to the cabinet. When the cover or lid *a* is closed upon the board *k*, the casing *j* with the panel *b* is received therein. Suitable clamps, clips or other retaining devices *l* serve to maintain the lid or cover *a* engaged with the board *k*. Thus, when the sound reproducing mechanism is required for use, the lid or cover *a* together with the board *k* are lifted together to expose the turntable and tone arm, while when the wireless receiving set is required, the board *k* and lid or cover *a* are first lifted together to permit the wireless sound amplifying device *c* to be substituted for the sound box *d* and the board *k* is then lowered again and the cover or lid *a* disengaged from the retaining devices *l* so that it may be raised to expose the panel *b*.

It will be understood that the invention is not limited to the details of construction hereinbefore described. Thus, the elements of the wireless receiving set may be provided as separate units not assembled on a panel but disposed within a suitable compartment or compartments formed in the lid or other containing casing. A frame aerial may be provided wound upon or in the lid or cover or upon a frame fixedly secured to the cabinet, or the frame may be mounted upon the cabinet that when required for use it may be readily elevated or turned into an operative position.

The tone arm of the machine may be adapted to be detached from a socket fitting mounted upon the motor-carrying plate of the cabinet at the inner end of the internal

horn or sound amplifier and the wireless sound amplifying device be provided for reception into the said socket and to be secured therein.

The wireless sound amplifying device in the construction represented in Figure 3 may be provided within a suitable casing fitted to the under-side of the board *k* and be adapted, when the board *k* is in position for the use of the wireless receiving set, to engage with a socket or other connection fitted upon the internal horn or sound amplifier of the machine. The said horn may for this purpose be provided with a branch or may be forked so that one branch serves for connection to the tone arm and the other for connection with the sound amplifying device of the wireless set.

It will be understood that the invention is not limited to any particular construction of sound reproducing machine or wireless receiving set. Moreover, the latter may if desirable be provided as a set capable also of transmission.

I claim:

1. A sound reproducing apparatus comprising in combination a single casing, means consisting of mechanism within the said casing for the production of sound from a record and comprising a sound-box, wireless receiving apparatus also within the said casing and comprising a sound amplifier, a single horn common to the said mechanism for the production of sound from a record and to the said wireless receiving apparatus, the said sound amplifier and the said sound-box being adapted to be alternatively applied for effective use on the said tone arm, the said casing comprising a recess for the alternative reception of the said sound-box and the said sound amplifier, substantially as described.

2. A sound reproducing apparatus comprising in combination a single casing, means consisting of mechanism within the said casing for the production of sound from a record and comprising a sound-box, wireless receiving apparatus also within the said casing and comprising a sound amplifier, a single horn common to the said mechanism for the production of sound from a record and to the said wireless receiving apparatus, the said amplifier and the said sound-box being provided with socket connectors for their alternative connection to the said tone arm, the said casing comprising a recess for the alternative reception of the said sound-box and the said sound amplifier, substantially as described.

3. A sound reproducing apparatus comprising in combination a single casing, a cover for the said casing, means consisting of mechanism within the said casing for the production of sound from a record and comprising a sound-box, wireless receiving ap-

- paratus, part of which lies in the cover of the said casing and comprising a sound amplifier, a single horn common to the said mechanism for the production of sound from a record and 5 to the said wireless receiving apparatus, the said amplifier and the said sound-box being provided with socket connectors for their alternative connection to the said tone arm, the said casing comprising a recess for the alternative reception of the said sound-box and the said sound amplifier, substantially as described.
- 10 4. A sound reproducing apparatus comprising in combination a single casing, a cover for the said casing hinged to the casing, means consisting of mechanism within the said casing for the production of sound from a record and comprising a sound-box, wire-
- less receiving apparatus also within the said casing and comprising a sound amplifier, a 20 support for the main part of said wireless receiving apparatus, said support being hinged at or about the same axis as that upon which the said cover is hinged to the said casing, a single horn common to the said 25 mechanism for the production of sound from a record and to the said wireless receiving apparatus, the said sound amplifier and the said sound-box being adapted to be alternatively applied for effective use on the said tone arm, the said casing comprising a recess for the alternative reception of the said sound-box and the said sound amplifier, substantially as described.
